UNITED STATES PATENT OFFICE.

SANFORD C. YOUNG, OF ERIE, PENNSYLVANIA, ASSIGNOR TO AMERICAN TIME LOCK COMPANY, WM. C. KRAMER, TRUSTEE.

FRAUDLESS BALLOT-MARKING MACHINE.

Application filed July 31, 1919. Serial No. 314,421.

To all whom it may concern:

Be it known that I, SANFORD C. YOUNG, a citizen of the United States, residing at Erie, county of Erie, State of Pennsylvania, have invented certain new and useful Improvements in Fraudless Ballot-Marking Machines; and I do hereby declare the following to be a full, clear, and exact description of the invention, such as will enable others skilled in the art to which it appertains to make and use the same.

My invention relates to means for preventing illegal or fraudulent voting, and embraces a means by which the limits of the voting period and the time as well, may be set in advance by a master keeper and the device put into condition for winding and setting by the official at the polling place.

I provide means by which, after the time measuring device or clock is wound and set, it cannot be molested or disturbed in any way until after the expiration of a protracted period, say eight or ten days, covering the time the ballots are counted and reported.

I provide means by which each ballot, when properly presented to the machine, is punched, stamped or impressed otherwise, means by which, when no ballot is presented, the impression device may not be operated, means whereby the insertion and stamping of more than one ballot at a single impression is prevented, and in general, means whereby surreptitious, premature, or fraudulent balloting is prevented during the period of voting, and for days after, rendered impossible.

My device is time-locking in character, in that it locks itself against access to its interior for a period and then throws aside a part which stops the unlocking operation.

In the accompanying drawings:

Figure 1 is a plan view;

Figure 2 is a side view; and Figure 2^a shows a clamp indicator;

Figure 3 is a side view of a modification; Fig. 3^a is a top view of a paper ballot gage; and Figure 3^b a side view;

Figure 4 is a plan view, partly in section, on a larger scale;

Figure 5 is a corresponding side view;

Figure 6 is a side view of a speed shift; and Figure 6^a is another side view of a speed shift;

Figure 7 is a plan view; and Figure 7^a is a side view of another form of paper gage,

to accomplish the same purpose as the part shown in Figure 3^a;

Figure 8 is a plan; and Figure 8^a is a side view showing holding pawl for the indicator of the center dial.

My present invention is an improvement over the machine described and claimed in my application Serial No. 202,642, filed November 17, 1917, entitled Ballot seal punch, now Patent 1,312,070, granted Aug. 5, 1919, and this improvement relates to means for simplifying the construction of my former machine and insuring accuracy and security.

In my device I provide a casing 1 secured to a pillar 2 upon a base 3. Projecting forward from the casing is an arm or bracket 4, and hinged in this arm or bracket at 5 and mounted to swing in a vertical plane is a swinging arm or bracket 6. Mounted on the forward end of said swinging arm is the housing 7. Slidably mounted in said housing is the staff 8, provided with a handle 9. The staff carries the ballot marking means and is permitted to be made effective for marking, and is prevented from being used at times by means presently to be described.

Immediately below the marking end of the housing 7 is mounted ballot clamp 10; said clamp is attached to the casing at 11 and is elastic so as to clamp firmly in place a ballot placed beneath it. I provide in the body of clamp 10 a way or groove 11', terminating in the rear in an opening 12. I mount in said way or groove a pointer or indicator 13, pressed forward by spring 14, and restrained by projection 15, extending through the slot 12. The pointer points to the exact spot which will receive the center of the impression. I provide on my swinging arm 6 a projection 16 for engaging the projection on the sliding pointer. Thus, after a ballot is centered, which is accomplished while the swinging arm is lifted, the arm in descending is made to withdraw the pointer out of the way of the housing 7 and the impression device.

Mounted on the top of the casing and hinged at 17 is a lid 18 which carries a crystal 19, indicated by dotted lines in Figure 4. Beneath the crystal is shown an annular dial 20 having hour marks on it. Within this dial is a second dial 21 mounted to turn within the dial 20 with hour marks thereon to indicate the period during which the

marker may be used and also indicating the time of opening and closing of the polls. Over the dials move the hour and minute hands 22 and 23 of a 24 hour time measuring device.

- 5 In the clock train indicated in Figure 5, the main spring 24 is connected to the usual gear 25. The plate 26 marks the top plate of the regular clock train.
- 10 The staff 27 is prolonged to the dial 21 carrying also the hand 23. About this staff, above the plate 26, is constructed mechanism to control the use of the ballot marking device at certain predetermined intervals
- 15 and for certain predetermined periods, and this mechanism I shall now describe.

On staff 27 I mount a pinion 28, which engages a gear 29 mounted on a staff carrying also pinion 30. This pinion 30 engages 20 gears 31 and 32 which are parallel and of the same diameter. Secured to the former gear 31 which is on the staff 27, is a pinion which engages gear 33, carrying also on the same staff a pinion 34 which engages gear 35 25 which fits loosely around sleeve 36, which sleeve is integral with or rigidly secured to gear 32. Immediately above my gear 35 I provide a plate stay 37, which serves to support the upper end of the staffs upon which 30 are mounted pinions 30 and 34. The wheel 32, the sleeve 36, hand 22 and dial 21 are all secured to turn together. The teeth of the gear wheel 32 are removed for a certain distance, that is, gear 32 is a mutilated gear.

35 During the arc in which the teeth are present, this gear is driven simultaneously with gear 31 by the pinion 30. When the gap is reached where the teeth are omitted, said pinion no longer drives gear 32. Motion

40 of a much slower character is imparted to the gear wheel 32 by the gear 31 through gear 33, pinion 34 and gear 35, made to engage wheel 32 by the following means.

On the upper face of gear 32 I provide a 45 circular ratchet 38. On the under face of wheel 35 and extending to the wheel 32, I provide pawl 39 engaging the circular ratchet 38 to drive wheel 32 with it at the same speed during the time that the gap in 50 wheel 32 is opposite the pinion 30. During the time the pinion 30 engages the teeth on wheel 32, said wheel 32 is driven faster than wheel 35 and the ratchet over-runs the pawl in wheel 35, said pawl having its end beveled or rounded to facilitate this. The purpose of this will be explained later.

Secured to the sleeve 36 above the plate or stay 37, is a notched disk 40. This disk turns in the same period as the hour hand 22; 60 its notch is so located that it is brought into engagement with a stop lever 42 just after the gear 32 becomes reengaged by pinion 30 and prevents the operation of the clock train—stops the clock until it is released upon

65 the complete rewinding of the clock after a

manner and by means presently to be described. This lever 42 is secured to a pivot staff 43, and extending from said staff at the top and constituting in effect an arm of the lever is an arm 44 extending at an angle to 70 the stop lever. The angle is so proportioned, that is, the arms are so set, that when the stop arm is out of the notch and sliding over the edge of disk 40, the shorter arm is opposite the bolt of a lock 45 in the lid of the casing, so the bolt can not be thrown, i. e. the device can not be unlocked when the clock train is in motion.

When the notch 41 comes opposite the stop lever 42, the arm 44 swings aside out of the way of the bolt, and any person having a key to lock 45 may open the device.

On the lower end of the same staff 43 I provide an adjustable spring arm 46 adapted to contact with the outer coil of the main spring. I provide a weak spring, indicated at 47, that tends to hold arm 46 in contact with the main spring. The arrangement is such that the main spring in expanding compresses the weak spring 47. The lever arm 42 is held against the periphery of the disk until the notch is reached, whereupon the main spring snaps it in and holds it there through its action upon the spring arm 46. The mechanism then can not be released until the main spring is completely wound up, when the spring 46 is adjusted to lift the lever out.

On the same staff 43 I mount a spring arm 48 extending forward to engage and arranged to stop the balance wheel 49. The parts are so arranged that the engagement of spring arm 48 with the balance wheel is simultaneous with the dropping of the lever 42 into the disk notch, and thus prevents the clock train from running till the nose of the lever 42 becomes jammed against a side of the notch.

I provide on sleeve 36, and frictionally secured thereto, an adjustable or extensible cam 50. The adjustment or extensibility is procured by making the cam in two parts angularly adjustable to each other about the sleeve, so as to make the bearing surface of the cam, and consequently the period of its functioning, longer or shorter. These two parts are of the same contour substantially. The upper one only appears in Figure 4, it being supposed that the mechanism is set to operate twelve hours, from 6 to 6, say. On looking at Figure 5, it will be noted that the upper of these parts is bent upward at one side at 51, so that it moves in the same plane as a spring bolt 52, which the other side of that part clears. Similarly the lower adjustable part is bent down at 53 to engage a spring bolt 54, which the other or right hand side of that cam part clears.

These spring bolts are mounted upon a sliding locking bolt 55 of the form shown

in Figure 5, having one arm 56 carrying bolt 54 and also arm or projection 57 carrying bolt 52. It will be seen that this sliding bolt will tend to be moved to the right or left by the springs of the bolts, but may be held by engagement of the cam surfaces with the arms. In Figures 4 and 5, the upper part has just passed the arm 56 and the sliding bolt has been snapped to the right, by pressure of one of the parts, as 51, on the spring bolt 52. Consequently, after this cam has rotated one-half revolution or for 12 hours, the locking lever 55 would likewise be snapped to the left by pressure of one of the parts, as 53 on spring bolt 54.

On the end of the sliding bolt 55 I mount an extension 58 slidably connected to bolt 55, there being a spring 59 in the connection between two corresponding projections, one on each part, so that there is a yield or give in the relative movement.

The extension 58 slides in a spline or way cut in a block 60 secured to the frame. Pivoted to said block 60 by a bolt 61, is an arm 62 provided with an oblique slot 63. In the forward end of the bolt extension is a pin 64 engaging said slot 63. Now it is evident that motion of the bolt 58 will tend to raise or lower arm 62. In the solid part 60, I make a hole 65 in which is mounted to slide a rod 66 which, at its lower end, engages with one arm of a bell crank lever 67 pivoted at 68. The other arm of the lever is arranged in front of a sliding staff mask 69. In this mask are holes through which keys may be inserted for winding and setting, when the holes in the mask are in registration with corresponding holes in the clock frame or plate.

I provide in the sliding mask certain slots, and I pass screws 70 and 71 through these slots, so that the mask is easily controlled and moved. In the rear or to the left of the mask I provide a recess or opening 72. I mount on the frame, or some other fixed part, a dog 73 adapted to enter the recess 72 when the slide mask 69 is pushed to the left by the bell crank 67, and hold the mask over the key holes in the clock frame and prevent insertion of a key. Release of the mask and uncovering of the key-holes is effected by means of a rod 74, the upper end of which is provided with a push button 75, which button may be exposed when lock 45 is unlocked and lid lifted. The lower end of the rod 74 engages and releases the holding dog 73 and is beveled or cam shaped to engage a corresponding shaped part on the mask.

I may provide depressions in the bolt 55 and a friction lock 76 adapted to enter either so as to hold the said sliding bolt in proper or justified position. In the forward end or part of the sliding bolt 58 is ar-

ranged a rod 77 which extends through swinging arm 6 to engage a cam 78 on staff 8. When handle 9 is pushed, the cam 78 will thrust rod 77 to the left, thus permitting the impression device 79 to print or mark the ballot. However this can happen only when the sliding bolt 58 is moved to the left and pivoted arm 62 is dropped, permitting the rod 77 to pass back over it. Neither can the swinging arm 6 be lifted until sliding bolt 58 is moved to the left so as to permit the downward movement of the left end of rod 77 sliding upon and pivoted on bolt 80. There is provided in said bolt a slot 81 to permit this sliding and radial movement.

About staff 8 I provide a sleeve 82 secured in the forward end of pivoted arm 6. I make a slot in this sleeve to provide a way for cam 78. Across said sleeve and immediately under spring 83 I insert a pin 84, as a support for said spring.

On each of the two parts of the cam 50 which controls the movement of the sliding bolt 55, I mount indicators 85, 86. These indicators move along scales properly graduated. By means of these indicators the adjustment of the parts of the cam with reference to each other, and consequently the time during which the ballot making impression device is operable, may be determined. In the upper part is a slot 50', through which the indicator of the lower part passes.

In Figures 8 and 8^a is shown in plan and side view, a detail of the construction of indicator points 85 and 86 and associated parts. For each of these indicator points is provided a spring pressed friction latch or pawl 89, in which I place a pin hole 90 and also a spring 91. I roughen or serrate the periphery of the center dial 21, as shown at 92, to enable the friction latches 89 to get a good hold.

On the pintle of the hinge upon which the swinging arm is mounted I provide two screw heads 5 with corresponding parts 80, as shown in Figure 4. To prevent removal of these screws and consequent removal of swinging arm 6, I drill in a solid part of the swinging arm 6 a hole for a screw 93. This screw passes into machined key seats 94 in the ends of pintle screw 80 to prevent the latter from being unscrewed and removed. The head of the screw 93 is exposed inside the casing, when the latter is unlocked and uncovered.

In Figure 3 I indicate a device of somewhat modified form. The ballot in this machine is stamped or marked near the edge, as in the case of a notary's seal. The clock mechanism in this form is identical with that previously described and is contained in casing 1. In the forward or left part of this modification I have indicated a count-

ing mechanism 94 of the Veeder or other suitable type, which is connected to the staff 8 so as to register every downward movement of the staff 8. Of course the counter 5 may be attached to register either on the downward or upward stroke, as desirable, and as is obvious.

Of course a Veeder or equivalent counter 10 may be used if desired, in the other modification.

I provide also in the modification shown in Figure 3 the sleeve 82 about the staff 8, and in the upper right hand section of this, as shown, I provide a slot or spline for the 15 cam or projection 78. It will be noted that the under side of this projection is cut squarely off so that it will strike squarely against the sliding bolt 58 when an attempt be made to force the staff downward at im- 20 proper time or on unlawful occasions, when the sliding bolt has not been drawn back.

To the left of the figure I provide a slot 25 for the counter actuating lever, as shown. I also provide a registering means in connection with the staff, whereby when the staff is once pressed down to make an impression it must be brought back far enough to insure registry before it can be again actuated. In the staff I provide a slot and a spring 30 pressed sliding piece 95. As the staff descends this piece 95 is thrust to the left by incline 96. In the bottom of the slot cut into the sleeve, and close to the staff 8, I leave a small piece of metal 97. If the incline or 35 guide 96 were not there, the piece 95 would engage the block 97 and prevent impression. Since the incline draws aside to the left of the piece 95, it permits the making of an impression because sliding piece 95 clears block 40 97. After the impression is made (or before) the sliding piece is spring drawn to the right behind the incline 96, and the sliding staff must be lifted to enable the 45 sliding piece to clear the incline before the next impression. Such an extent of movement insures the registry of the counting device.

I may also provide a signal device, here 50 shown as bell 98, to operate every time an impression is made. The bell 98 may be made to ring by the downward movement of the staff 8.

In Figure 3 I show a means 99 for preventing the insertion of more than one ballot at a time and for preventing the operation 55 of the impression stamp where no ballot is inserted. The opening 100 into which the ballot is thrust is a slot just wide enough to accommodate a piece of paper of the thickness of a ballot but not wide enough to admit two or more sheets. It will be noticed that as the slot 100 is wide enough for only one ballot, any one lying above said ballot will be stopped or held back by the piece 99.

65 The exact gage of the slot between part 99

and the base 3 into which the ballot is inserted is determined by taking a piece 101 of a ballot, giving it the somewhat forked shape indicated by the shape of part 99, placing same between part 99 and the base 3, and securing the two together by screws 102, Figure 3^a and Figure 3^b. These screws are each equipped with a light coil spring 103 between the head and plate 99 or seat in the plate, so that the plate is held merely by light spring pressure. The holes for the screws are not deep enough to permit greater pressure being exerted by the screws. This contraction will determine the exact thickness of the slot necessary for the admission of a ballot 104. For ease in thrusting in the ballot the thickness of the slot may be increased by superposing a piece of thin tissue paper. This will make the thrust of the ballot into the slot slightly more free but will exclude a second ballot. The slot is reached through opening 105.

I also provide means for preventing the operation of the impression device when no ballot is inserted. In plate or gage 99 I 90 mount to slide vertically a pin 106. This pin is provided near its upper end with a hole 107. Where a ballot 104 is inserted the pin 106 rests upon the ballot and leaves the opening opposite a bolt 108 sliding in a seat in the sleeve 82. If the hole in the pin is not opposite the bolt 108 said bolt can not slide. It then prevents the descent of the staff 8 on account of a projection 109 on said staff which contacts with the bolt. If 95 the thrust of the bolt to the right in Figures 3 and 3^b is permitted, it is thrust into the hole by the same projection 109. The bolt 108 is provided with a light spring 110 to retract it after a thrust. In the base 3 100 directly under the pin 106 I provide a recess 111, into which the pin may drop when the recess is not bridged by a ballot 104. I provide also on pin 106 an arm 112 extending out over the impression device 79. 110 The pin 106 is lifted by this arm 112 when the impression device is raised by the spring 83 and staff 8. It follows the impression device down unless prevented by a ballot over the recess 111.

I may provide another means shown in Figures 7 and 7^a to prevent the operating if more than one ballot be inserted, and also to prevent the operation of the impression device when no ballot has been inserted. Disk 113 is ground off, commencing with one side of the slot, on a slightly diminishing radius to the other side of the slot. That is, it is an oval cam in shape. The difference is so minute that it can not be shown in the drawing. This roller or disk, provided with slot 114, is mounted in spindle 115. This spindle 115 is in two parts, ends abutting, and connected by hair spring 116, one end of the spring being connected 115

to each of the parts of the spindle. As indicated the disk is on one of the spindle parts. On the other part I put a toothed pinion 117. The two ends of the spindle 5 are mounted in some fixed part. On the impression device 79 I put a pin 118 and attach to said pin a rack 119 adapted to engage pinion 117 and turn it. The end of the pin 118 extends out over the disk 113 10 and under certain conditions will enter the slot 114 and permit an impression to be made. At other times said pin 118 will engage the periphery of the disk 113 and prevent impression being made. The registry 15 of the slot with the path of the descending pin 118 is effected by the insertion of a ballot of the proper thickness, as will be understood by the following.

It will be observed that the turning of 20 the part of the spindle on the left, through the pinion 117 and rack 119 tends to effect the turning of the spindle part to the right and the attached disk. The arc through 25 which the latter may be turned is determined by the thickness of the sheet or ballot inserted below it. This arc is so calculated and the disk so shaped that this brings the slot directly at the right place beneath the pin 118, and impression may 30 be made. If no ballot be inserted the disk will turn far enough to bring the slot beyond position. If two or more ballots be inserted the disk will not be turned far enough to bring the slot into position. 35 The operation of the device will be clearly understood from the above, but is again recited below.

When the two part cam has thrust the bolt 55 to the left in Figure 5, the bolt 58 40 will also be drawn to the left by means of spring connection 59. The withdrawal of bolt 58 will effect the lowering of pivoted arm 62, which will permit thrust of rod 77 to the left by the descending staff 8 and the 45 making of an impression. It also prevents the swinging of rod 77 on the pivot 80 when the swinging arm 6 is lifted. Also the downward movement of pivoted arm 62 will operate bell crank 67, thrust sliding mask 50 69 to the left where it will be locked by dog 73, thus preventing the insertion of winding and setting keys until after lock 45 has been unlocked, the lid 18 lifted and the 55 button 75 pressed to push out the dog and thrust the sliding mask to the right. But if at the time the sliding bolt is thrust to the left by the two-part cam 50, a key be left in a key-hole 120, 121, the mask 69 can not be slid to the left, the bell crank 67 60 cannot operate, the pivoted arm 62 cannot descend, and the sliding bolt 58 cannot move to the left to permit any operation of the marking device until such keys are removed. But in this case the spring 59 will 65 be compressed so that the unlocking may

occur and impression be made as soon as the keys are withdrawn from holes 120, 121.

It is also apparent that when the main spring is wound up spring 47 will cause a contra-clockwise movement of staff 43. This 70 will withdraw lever 42 from recess 41 in disk 40, also spring arm 48, from contact with the balance wheel 49. It will also place the short arm 44 in the path of the bolt of lock 45, thus permitting the clock-work 75 to run and be set at the proper times and preventing the unlocking of the lid 18 and lock 45, until such time as disk 40 has made a complete revolution again bringing slot 41 in registration with arm 42, at which 80 time the main spring will have run down, creating pressure upon spring arm 46 sufficient to over-ride the power of spring 47, thus causing a clockwise turning of staff 43 which replaces arm 42 in the slot 41 of disk 85 40 and spring arm 48 against balance wheel 49, effecting an immediate stopping of the clock train and preventing the movement and setting thereof until after the main spring has been completely rewound. This 90 clockwise movement of the staff 43 turns the short arm 44 away from the lock bolt and permits the lock 45 to be unlocked.

I have thus devised a machine a number 95 of which is contemplated for each county or city, one or more for each polling place, for all of which some official, say a master keeper, has a master key for lock 45. Before the machines are distributed to the various polling places, the master keeper may 100 unlock the lock 45, lift up lid 18, and set indicators 85 and 86 for the proper opening and closing times. At the same time he will push button 75 to expose the winding and setting staffs through keyholes 120 and 105 121, so that the election officers may wind and set the clocks moving when ready to begin receiving votes. The lock 45 is then locked and the machines distributed to the proper election officers. The election officers 110 will receive with the machines winding and setting keys, or one key may do for both. These keys must be of sufficient length to pass through base 3, proper holes being provided. But the election officer is provided 115 with no key that will unlock lock 45.

The election officer must first wind the main spring completely up before the clock can start. That winding is sufficient to run the clock the required length of time, say 120 8 or 10 days, to permit the ballots to be counted and the result reported, during which time no access to the machine may be gained with any key, even the key to lock 45. When wound the clock may be properly set to actual time. The election official will then withdraw the setting and winding keys, and the machine is ready to operate upon the ballots, one at a time, and may be used for 125 the period as set by the indicators 85 and 86, 130

at the end of which time the locking mechanism prevents further operation of the marking device. The clock, however, continues to run during the vote counting and reporting period, say 8 or 10 days, until the inner lock, as described, prevents further movement of the clock train and the unlocking of lock 45 by the master keeper's key is again rendered possible.

10 Thus it will be obvious that from the time of the winding and setting of the clock and withdrawal of the keys until the vote counting and reporting period is ended and the clock has stopped, any access to the works, 15 insertion of any key, or any other molestation is rendered impossible. Furthermore, the only way to gain access for an indefinite period after the stopping of the clock, is by way of the master keeper's key 20 to lock 45. This lock must be unlocked and the release button 75 pressed, before it is again possible to wind and start the machine for another voting period.

It will be noted that when the machine 25 is once put into use it can only be used for a period predetermined by the master keeper. Thus, if the clock be started on the day preceding election, the period for which the device is open for use, can not coincide with 30 the period set by law. If any unscrupulous or careless official has used the machine he will be obliged to turn it in and secure a special machine, of which a few would generally be kept in reserve, thus calling attention to his surreptitious or improper treatment 35 of the machine at once.

It will thus be apparent that I have devised an apparatus which can be constructed at little cost, one which is adapted to be 40 used by the most ignorant voters, and one which imperatively demands the attention of the precinct officials within the proper time to permit voting, and which, after the expiration of that time locks itself up against 45 all manipulation or access for a prolonged period. The master keeper has to set the machines and distribute them from his central office in time for election day. After 50 election and after the votes are counted and compared with the counting mechanism, if one be used, the machines are again collected and held for the next occasion.

The machines are small, are suitable to 55 any booth, adapted to any ballot or to any voting conditions whatsoever without cost beyond that for the machines themselves. They are not liable to damage or to get out of order, and cannot be molested or changed save by violence.

60 The stamp or impression die may be varied to suit any particulars or local conditions, and it is my intention to provide a special marking, etc., for each precinct where a machine may be used. It may be 65 an embossed, inked, printed, perforated,

burnt or branded, or shredded mark, or in fact a mark of any kind that can be made by impression or combination of the foregoing. The marks may be changed from time to time. It will be impossible to change them while the machine is open for use and for a period afterward.

The impression of the stamp shows that the ballot has been voted, and no ballot can be considered or counted as a legal ballot 75 unless stamped or impressed in the manner indicated.

The modification of Figure 3 may be used as a seal is used after a signature by the election official who certifies to the authenticity and validity of the ballot voted at that precinct as an official ballot, and this device may be used with or without the standard form to be used by the voter.

I have thus produced a fraud-proof ballot 85 validating and marking machine.

Having thus described my invention, what I claim as new and desire to secure by Letters Patent of the United States is:

1. In combination, a marking device, a clock train, marker controlling means controlled by the clock train for allowing marking operation of the device during a predetermined time and thereafter preventing marking operation, a casing inclosing the clock train and marker controller, and means for preventing the opening of the casing rendered operative upon the starting and inoperative upon the stopping of the clock train.

2. In combination, a marking device, a clock train, a movable element actuated by the clock train and allowing operation of the marking device during a portion of its movement and preventing marking operation during the remainder of its movement, means for stopping the clock train before the movable element has moved beyond a certain position, a casing inclosing the clock train and movable element, and means for preventing the opening of the casing rendered operative upon the starting and inoperative upon the stopping of the clock train,

3. In combination, a marker, a clock train, an adjustable cam actuated by the clock train, means connecting the cam and marker and freeing the marker for marking operation during a predetermined portion of the movement of the cam and preventing marking operation during the remainder of the movement of the cam, means for stopping the clock train before the cam has moved beyond a certain point, a casing inclosing the clock train and cam, and means for preventing the opening of the casing rendered operative by the starting and inoperative by the stopping of the clock train.

4. In a ballot marking device, in combination, a marking stamp, a casing, a clock train therein, an adjustable means for de-

- termining the length of a period when the stamp is operable, a suitable means for determining when the period of operableness may occur, and self-locking means operated by the clock, whereby the clock train prevents unlocking of the casing for interference at the close of said period of operableness for a protracted period and then permits the casing to be unlocked. 5
- 10 5. In a device for marking ballots, in combination, an operable stamp, a bolt preventing said stamp from being operated except at predetermined and appointed times, time measuring means whereby said bolt becomes ineffective at the beginning of said period and again becomes effective at the close of the period, a casing for said time measuring means, a door and lock for said casing, means for preventing the opening of the lock, a device operated by a part of the time train to withdraw said preventing means, and a device for preventing the energizing and setting of said time train and a part accessible on unlocking adapted to move 25 said last named preventing device. 6. In a time controlled marking machine, in combination, a ballot marking device, time controlling means whereby operation of said device becomes possible at a time predetermined in relation to time shown by said machine, means whereby operation of said device becomes impossible at a time predetermined in relation to time shown by said machine, means whereby said device is locked against operation and readjusting for operation to all parts whereby rewinding, resetting or adjusting in any manner may be prevented, for a period predetermined after the locking of said device 40 against operation. 7. In a ballot marking device, in combination, a casing, a ballot marker, means for preventing and permitting the use of said device and adapted to prevent the surreptitious marking of ballots, a clock train for effecting such control, which clock train locks itself against access to itself or interior at all times when said clock train is in motion and which locks itself against movement at a time predetermined in relation to time shown by said clock train and which cannot be again made to move or set in motion until rewound, and means for winding and setting said clock train, which means can only be used during the time the time clock train is locked against motion. 45 50 55 60 65 8. In a device for marking ballots, an impression device controlled by a time clock, a casing for said time clock with a trap door adapted to lock said time clock within said casing, and an additional lock in connection with said time clock adapted to lock said trap door against opening when the said time clock is in motion and which lock will prevent access to said clock train although the first mentioned lock be unlocked. 9. In a marking machine, in combination, a clock train, an hour and a minute hand, an annular dial, over which said hands move, a rotating scale within said annular dial and adapted to move with one of said hands, pointers past which the scale moves, a two-part cam connected to the clock train, said parts being angularly adjustable and connected each to a pointer, a stamp, a bolt for controlling the operation of the stamp, and means connected with the two-part cam to actuate the bolt whereby the stamp is rendered operable for a period determined by the position of the pointers in relation to each other and to the rotating scale. 70 75 80 85 90 95 100 105 110 115 120 125 130
10. In a marking machine, in combination, a clock train, an hour and a minute hand, an annular dial, over which said hands move, a rotating scale within said annular dial and adapted to move with one of said hands, pointers past which the scale moves, a two-part cam connected to the clock train, said parts being angularly adjustable and connected each to a pointer, a sliding bolt adapted to be in engagement with the said cam and to be moved at a time determined in accordance with the position of one cam part, a stamp, a lock for said stamp controlled by said bolt, and releasable when the cam comes into its bolt-moving position, said bolt being also moved to restore the stamp lock at a period determined in accordance with the angular adjustment of the two-part cam. 10. In a marking machine, in combination, a stamp, a clock train controlling the period for making said stamp operable, a casing, a lock thereon, an arm for stopping said lock from being unlocked, two parallel wheels in the train, a pinion for engaging and driving said wheels, one of said wheels being fast on the main staff and one of said wheels being free on the main staff, a notched disk, a lever for said notch connected to said free mounted wheel, a third gear wheel, a pawl and ratchet connection between said last named and the free mounted wheel, and a reducing train between the fast wheel and the third gear wheel whereby the free or second wheel may be turned at very slow speed till the lever drops into the notch and moves said cam. 11. In a marking machine, in combination, a stamp, a clock train controlling the period for making said stamp operable, a casing, a lock thereon, an arm for stopping said lock from being unlocked, two parallel wheels in the train, a pinion for engaging and driving said wheels, one of said wheels being fast on the main staff and one of said wheels being free on the main staff, a notched disk, a lever for said notch connected to said free mounted wheel, a third gear wheel, a pawl and ratchet connection between said last named and the free mounted wheel, and a reducing train between the fast wheel and the third gear wheel whereby the free or second wheel may be turned at very slow speed till the lever drops into the notch and moves said cam. 12. In a time controlled ballot stamping device, in combination, a casing, a ballot stamp, a time train adapted to determine the time and period of operableness for said device, means whereby said time train may be energized and set, by means of a key, a key-hole masking slide, means for automatically holding the slide in masking position during the period of stamp operableness, means whereby said slide may be moved 130

from key-hole masking to key-hole open position, and means whereby the device keeps itself locked against access to said slide moving means for a period protracted beyond the period of stamp operability, and then permits itself to be unlocked.

13. In a time controlled ballot marking machine, in combination, a ballot stamp, a spring driven clock train controlling the period during which said stamp may be actuated, a casing, a lock for said casing, an arm for preventing said lock from being unlocked, a staff on which said arm is mounted, a spring and an arm on said staff adapted to contact with the winding spring and adapted when the winding spring is completely wound up to permit the lock stopping arm to be turned in said spring to lock-stopping position.

14. In a time controlled ballot marking machine, in combination, a ballot stamp, a spring driven clock train controlling the period during which said stamp may be actuated, a casing, a lock for said casing, an arm for preventing said lock from being unlocked, a staff on which said arm is mounted, a circular notched disk, means connected with the clock train whereby said cam is caused to move slowly, an arm mounted on said staff and adapted to rest upon the disk, a spring to hold it there, said arm adapted, when resting upon the disk, to hold the lock stopping arm in locking position and to drop into the notch when the clock train becomes run down to swing the lock stopping arm from lock stopping position.

15. In combination, a casing, a time train adapted to lock and unlock itself in said casing by parts while in motion and which cannot be stopped, rewound, reset, or adjusted while in motion, a movable member projecting into said casing and arranged to be engaged or non-engaged by a marking device, which engagement and non-engagement prevents and permits the actuation of said marking device at periods predetermined in relation to time shown by said clockwork.

16. In combination, a clock train adapted to lock itself within a casing substantially as described, a casing for said clock train, a lid on said casing, a lock to lock said lid, a special lock connected with said clock train

to lock said lid lock from the inside of said casing, a special staff in said clock train in connection with means adapted to move a locking lever to and fro at times predetermined in relation to time shown by said clock, a part fitted in an opening in said casing which part is engaged and disengaged by the said to and fro movement of said locking lever which engagement will prevent and which disengagement will permit the operation of said part fitted in said opening during periods of time predetermined in relation to time shown by said clock train, and a marker connected to and capable of marking operation only with operation of said part.

17. In combination, a marking device, a spring actuated clock train, marker controlling means controlled by the clock train for allowing marking operation of the device during a predetermined time and thereafter preventing marking operation, a casing enclosing the clock train and marker controller, a door for the casing, a lock for the door, a key hole in the casing for winding the spring, a key hole masking slide, means to move the slide to masking position upon starting of the clock train, means to move the slide from masking position accessible only through the casing door, and means for preventing unlocking the door rendered operative upon the starting and inoperative upon the stopping of the clock train.

18. In a ballot marking device, a movable marker, a clock train, marker controlling means controlled by the clock train for allowing marking operation of the marker during a predetermined time and thereafter preventing marking operation, a casing enclosing the clock train and marker controller, means for preventing the opening of the casing rendered operative upon the starting and inoperative upon the stopping of the clock train, a counter for recording the number of marking movements of the marker, means for preventing marking movement of the marker too slight to cause the counter to register, and means to prevent marking movement of the counter except when one single ballot is in place to be marked.

In testimony whereof, I affix my signature.

SANFORD C. YOUNG.
